UNITED STATES PATENT OFFICE.

FRANZ FETTBACH AND GEORG LIECKFELD, OF HANOVER, GERMANY,
ASSIGNORS TO GEORG WEINHAGEN, OF MILWAUKEE, WISCONSIN.

WINDING MECHANISM.

No. 815,692.

Specification of Letters Patent.

Patented March 20, 1906.

Application filed October 23, 1901. Serial No. 79,742.

To all whom it may concern:

Be it known that we, FRANZ FETTBACH and GEORG LIECKFELD, subjects of the German Emperor, residing at Hanover, Province of Hanover, Germany, have invented new and useful Improvements in Winding Mechanism, of which the following is a full, clear, and exact description.

The present invention relates to winding mechanisms such as are sometimes employed for making small boxes.

The invention comprises the details of construction hereinafter set forth, and particularly pointed out in the claims.

15 In order to render the present specification easily intelligible, reference is had to the accompanying drawings, in which similar letters of reference denote similar parts throughout the several views.

20 Figures 1 to 8 show the winding mechanism, Fig. 1 being a part sectional elevation of the feed device for the strip to be wound; Fig. 2, a longitudinal section through the feeding-checks and the cutter mechanism; 25 Fig. 2^a, a cross-section through Fig. 2; Fig. 3, a similar sectional elevation to that of Fig. 2, showing the feed-checks in their rearward position; Fig. 4, a longitudinal section through the shaft-bearings, showing the shaft on 30 which the parts of the box are wound; Fig. 5, a similar elevation in part, showing the clamping device for the strip in operative position; Fig. 6, a part sectional elevation showing in section the mechanism for operating 35 the clamping-finger; Fig. 7, a plan of Fig. 6; Fig. 8, an end elevation of the clamping-finger-operating gear, and Fig. 9 a plan view of the whole machine.

According to the present invention, the 40 strip of material to be wound is first advanced by clamping-checks over the end of a rotary shaft, then automatically clamped to the said shaft end by means of a clamping-finger, then rolled up to the desired degree, and automatically pushed off the end of the shaft.

The feed-checks 7 and 8, the latter of which is provided with ribs 18, which lie on the adhesive side of the strip, are moved backward and forward in suitable guides by means of a 45 lever 10, pivotally connected to a rock-lever 9, operated by a cam-disk 13 and held against the same by a spring 16.

As will be seen from Fig. 2, the top cheek 8 is pressed onto the strip 1 by a light spring,

which as soon as the end of the strip fed has 55 been held by a clamping-finger hereinafter described, will allow the cheeks to slide back over the strip without pulling it back. The cutter 11, Figs. 1 to 3, is vertically reciprocated by means of a rock-lever 12, having its 60 roll held against the cam 13 by means of a spring 17. This roll is operated to cut off the strip by means of a cam-surface 15, lying in a different vertical plane to that of the cam-surface for the lever 9. Thus when the strip 65 has been sufficiently wound onto the end of the shaft it is automatically cut off. The clamping-finger 14, which retains the end of the strip 1, is illustrated in Figs. 4 to 6. It is 70 rigidly connected to a short lever 19, pivoted to a sleeve 21, adapted to slide on a sleeve 20 of the shaft 6, but keyed to the same, so as to rotate with it. A nose 19' of the said lever 19 extends down into a groove 29 of the shaft 6, and when this nose on the movement 75 to the left of Fig. 4 strikes the end of the groove 29 the said lever 19 is turned on its pivot against the action of a spring and forces the finger 14 down onto the end of the shaft, thus clamping the end of the strip to the said 80 shaft and causing the same to be taken round when the shaft rotates. The sleeve 21, carrying the operating mechanism for the clamping-finger 14, is operated by means of a ring 24, loosely mounted thereon and pivotally 85 connected to the bifurcated end of a rod 25, having a roll 26 adapted to be operated by a rotary cam-disk 27, driven by suitable means. The shaft 6 is keyed to a sleeve 20, but is capable of axial movement therein, the said 90 sleeve being mounted to rotate in bearings 22 and 23, but not being capable of longitudinal movement therein. The sleeve 20 carries the driving-pulley 30, loosely mounted thereon, and a coupling-half 31 fast thereon, so 95 that when the two parts 30 and 31 are in engagement the shaft 6 and sleeve 20 will be rotated. The coupling-half 30 is operated by a ring 32, loosely mounted thereon and in connection with the fork of a rod 31, having a 100 roll 34, held against a cam-disk 35 by means of a spring 40. The rod 25 is held against its cam-disk 27 by means of a spring 28. When the projections on the cam-disk 35 throw the rod 33 over to the right of Fig. 4, the coupling will be engaged and the shaft 6 and sleeve 20 will be rotated. When sufficient material has been wound onto the end of the

shaft 6, the latter is pulled back to the right of Fig. 7, and the end of the sleeve 20, which does not follow this movement, will push the roll off the end of the shaft, so that it may fall down into any suitable receptacle. Previous to this operation the cutter, which is so timed, has severed the strip. The axial movement of the shaft 6 is produced by the ring 36, coupled to the end of the shaft and also to the fork of a rod 37, having a roll 38, which is held against a cam-disk 39 by means of a spring 41. When the cam of this disk comes round, it pushes the rod 37 to the right, Fig. 7, and pulls the shaft 6 along in the same direction, so that the roll will be pushed off the end of the said shaft 6. The shaft 6 is then again advanced, and the clamping-cheeks are timed to advance the end of the strip at this moment, so that as the sleeve 21 is moved forward the finger 14 will clamp the advanced end of the strip for the next operation.

We claim as our invention—

1. In a winding mechanism for box-making or other machines the combination of a rotary shaft on the end of which the material is wound, a pair of reciprocatory feed-cheeks to advance the end of the strip of material

over the end of the shaft, a sleeve in which said shaft is axially movable and having a finger pivoted therein, a nose extending from said finger, a groove in the shaft in which said nose lies, a spring to normally hold the said finger up off the shaft end, the said groove being so located that its end forces the finger down on the shaft when the sleeve is advanced thereon substantially as described. 35

2. In a mechanism of the class specified, the combination of means for advancing the strip of material a step toward and over the end of the rotary shaft, a pivoted finger adapted to clamp the said material end to the end of the shaft a sleeve longitudinally movable on said shaft to carry said finger and means in connection with said finger to move it down onto the strip end when the said sleeve is moved along the shaft and to retain it down until the winding operation has been completed substantially as described. 40

In witness whereof we have hereunto set our hands in presence of two witnesses.

FRANZ FETTBACH.
GEORG LIECKFELD.
